DESIGN FOR A HANDBAG

Ida Jolles, New York, N. Y.

Application May 4, 1943, Serial No. 110,116

Term of patent 3½ years

To all whom it may concern:

Be it known that I, Ida Jolles, a citizen of no country, but have declared my intentions of becoming a citizen of the United States of America, residing in the city of New York, county of New York, and State of New York, have invented a new, original, and ornamental Design for a Handbag, of which the following is a specification, reference being had to the accompanying drawing, forming part thereof, wherein,

The characteristic feature of my design resides in the portions shown in solid lines.

I claim:

The ornamental design for a handbag, substantially as shown and described.

IDA JOLLES.
